[57] CLAIM

The ornamental design for a pocket racing game box, as shown and described.

DESCRIPTION

FIG. 1 is a top plan view of a pocket racing game box showing my new design.

FIG. 2 is a front elevational view thereof;

FIG. 3 is a rear elevational view thereof;

FIG. 4 is a right side elevational view thereof; and

FIG. 5 is a left side elevational view thereof.

FIG. 6 is a perspective view thereof.

It is noted that the bottom is flat.
